UNITED STATES PATENT OFFICE.

OTIS F. AMBURN, OF GALVA, ILLINOIS, ASSIGNOR, BY DIRECT AND MESNE ASSIGNMENTS, TO JOHN T. CLARK AND JOHN G. MARTZ, OF BIG RAPIDS, MICHIGAN.

COLLAR OR CUFF BUTTON.

SPECIFICATION forming part of Letters Patent No. 701,244, dated May 27, 1902.

Application filed September 7, 1900. Serial No. 29,319. (No model.)

To all whom it may concern:

Be it known that I, OTIS F. AMBURN, a citizen of the United States, residing at Galva, in the county of Knox and State of Illinois, have invented certain new and useful Improvements in Collar or Cuff Buttons, of which the following is a specification.

This invention relates to improvements in collar and cuff buttons, and has for its primary object to enable the ready and easy insertion of the button through thick and stiff material and the securing of the button as against accidental displacement when once it is inserted in position.

Another object is to have the button of such character that it will not damage or injure the cloth by contact therewith when in use and which may be readily and quickly inserted or removed when desired.

These and such other objects as may hereinafter appear are attained by the devices illustrated in the accompanying drawings, in which—

Figure 1 represents a perspective view of a collar-button embodying my invention, showing the same in position for insertion in a buttonhole. Fig. 2 is a similar view showing the button turned to position to secure the same in a buttonhole. Fig. 3 is a vertical section thereof. Fig. 4 is a detail section thereof. Fig. 5 is a perspective view of the base, and Fig. 6 is a perspective view of the head and shank.

Similar letters of reference indicate the same parts in the several figures of the drawings.

Referring to the drawings, A represents the base of the button, which may be of any suitable shape and size, being shown in the drawings as an elliptical disk. From the center of the base rises a flat post B, through which and through the base is a passage C, open at both ends, the top of the post being provided with a transverse notch D, which intersects the passage C. In said passage is located a spindle E, having near one of its ends an enlargement, preferably in the form of a head F, between which and an annular shoulder G, near the upper end of the passage C, is confined a coiled spring H, surrounding the spindle and

bearing at one end against said enlargement and at the other end against said shoulder, so that the spring has a constant tendency to force the spindle out of the passage at the lower end thereof. The opposite end of the spindle projects up through the notch D and has secured thereon a cross-piece I, which constitutes the head proper of the button, the length and width of the head I corresponding with that of the post B, so that the edges thereof lie flush, and when the parts are in the position shown in Figs. 1 and 3 the head in effect constitutes a continuation of the post. The head I is held against the post by the pressure of the spring H, and to more effectively prevent the accidental shifting of the head when being inserted into or withdrawn from a buttonhole the meeting faces of said members are respectively concaved and convexed, the head being shown concaved and the post convexed in the drawings. The head is also somewhat reduced and pointed at its center to facilitate its introduction into a buttonhole.

The head F of a collar or cuff button embodying the invention is small, and by reason of this and by reason of its tapering shape it does not afford a very good purchase for the fingers in the process of lifting it under any of the conditions of actual use. It is of course desirable to use a spring of sufficient strength to prevent the head from being accidentally lifted, and in proportion to the increase in the strength of the spring the difficulty in lifting the head increases. It is for this reason that I expose the lower end of the spindle at the under side of the base of the button. By so exposing it pressure may be exerted upon it, and in this way the head may be easily lifted. It will also be noticed that the post is wider at the end carrying the head I than at the end attached to the base, so as to assist in preventing the accidental slipping thereof through a buttonhole. To aid the convex and concave meeting faces of the post and head in preventing the turning of the head in being inserted in or removed from a buttonhole, I also prefer to provide said members with a dowel-pin and socket, the pin being preferably beveled, so that the head will

easily ride over it when turned into alinement with the post. In the drawings I have shown the dowel-pin or some equivalent projection on the post, as at J, and the socket K therefor in the head I.

- 5 In Fig. 1 the button is shown in position to be inserted into a buttonhole, the head I being in alinement with the post, and the edges of both of said members being rounded and 10 the members themselves being flat they may be readily forced through a buttonhole in the thickest and stiffest material. After being passed through the button hole or holes until the head I passes beyond the buttonholes 15 through which it has been inserted the head is first lifted far enough to clear the post and then rotated to a position at right angles with the post, as shown in Fig. 2, when under the influence of the spring H the head will be 20 drawn down into the notch D in the post and there held against rotation by the engagement of its sides with the walls of the notch. To remove the button or to disengage the buttonholes of a collar or cuff therefrom, the 25 head must be raised out of the notch and clear of the post and then turned to a position parallel with the post, which will allow the ready removal or disengagement of the collar or cuff.
- 30 This device is exceedingly cheap and durable, all of its parts being substantially solid, the button cannot rotate in a buttonhole because of the flat post inserted therein, and the tension of the spring will be sufficient under

all conditions to prevent the accidental detachment of the button while in use.

Having thus described my invention, what I claim, and desire to secure by Letters Patent, is—

1. In a button, the combination with the 40 base and a post rising therefrom, of a longitudinal passage extending through said post from end to end and open at both ends, an endwise-movable spindle located in said passage and having its lower end exposed at the 45 under side of the base, a head secured to the upper end of said spindle, and a spring engaging the spindle and tending to force it out of the passage at the lower end thereof, substantially as described. 50

2. In a button, the combination with the base and a post rising therefrom, said post having through it a longitudinal passage open at both ends, of an endwise-movable spindle located in said passage and having at its lower 55 end an enlarged head exposed at the under side of the base, a head secured to the other end of said spindle and adapted to seat upon the upper end of the post, and a spring surrounding the spindle and bearing in one direction against the post and in the other direction against the enlarged head of the spindle, substantially as described. 60
